US0D1016879S

(12) **United States Design Patent** (10) Patent No.: **US D1,016,879 S**
(45) Date of Patent: ** Mar. 5, 2024

(54) CAMERA DEVICE WITH ADJUSTABLE BASE	3,906,592 A	9/1975	Sakasegawa et al.
	4,309,096 A	1/1982	Sethi
	D268,672 S	4/1983	McPherson
	4,439,643 A	3/1984	Schweizer
(71) Applicant: GOOGLE LLC , Mountain View, CA (US)	D296,013 S	5/1988	Layne
	5,039,366 A	8/1991	Strattman
	D349,714 S	8/1994	Hasegawa
(72) Inventors: Mark Woolhiser Huang , San Francisco, CA (US); Sung Bai , San Jose, CA (US); Maj Isabelle Olsson , Sunnyvale, CA (US); Albert Lee , San Francisco, CA (US)	D353,904 S	12/1994	Swanson
	5,439,387 A	8/1995	Hayashi
	5,441,224 A	8/1995	Ludwig
	5,482,234 A	1/1996	Lyon
	D390,482 S	2/1998	Pasquarette
	D394,274 S *	5/1998	Suzuki .....
	D399,584 S	10/1998	D16/202
	6,007,136 A	12/1999	Zittwitz et al.
	D427,696 S	7/2000	Scott
	D431,307 S	9/2000	Zelina, Jr.
	D433,994 S	11/2000	Jobs et al.
	6,176,142 B1	1/2001	Ericson
	6,196,915 B1	3/2001	Schiedegger et al.
(21) Appl. No.: 29/910,571	D440,330 S	4/2001	Scott
(22) Filed: Aug. 22, 2023	6,234,277 B1	5/2001	Kaczmarek
	6,644,617 B2	11/2003	Pitlor
	6,732,983 B1	5/2004	Blake et al.
	D506,565 S	6/2005	Yurich
	D509,842 S	9/2005	Ou
	D528,576 S	9/2006	Chung
	7,162,790 B1	1/2007	Daniels
	D537,784 S	3/2007	Suckle et al.
	D553,659 S	10/2007	Kweon
	D554,171 S	10/2007	Deng
	D591,267 S *	4/2009	Files .....
	D593,071 S	5/2009	Laituri et al.
	7,551,225 B2	6/2009	Overstreet
	7,641,161 B2	1/2010	Bauer
	D623,594 S	9/2010	Akana et al.
	D627,815 S *	11/2010	Oba .....
	D640,721 S	6/2011	Satine
	D644,259 S	8/2011	Barley
	D659,282 S	5/2012	Richmond
	D659,497 S	5/2012	Blazevic
	D662,122 S	6/2012	Goodwin et al.
	D670,426 S	11/2012	Bouroullec et al.
	D691,587 S	10/2013	Ferber et al.
	D697,481 S	1/2014	Akana et al.
	D700,075 S	2/2014	Bould et al.
	D701,258 S	3/2014	Huang
	D702,275 S	4/2014	Ying
	D708,378 S	6/2014	Recker et al.
	D720,755 S	1/2015	Nokuo
	D722,635 S	2/2015	Richardson et al.
	D729,773 S	5/2015	Salojarvi et al.

CLAIM

The ornamental design for a camera device with adjustable base, as shown and described.

DESCRIPTION

FIG. 1 is a front and right side perspective view of a camera device with adjustable base showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines depict portions of the camera device with adjustable base in which the design is embodied that form no part of the claimed design.

1 Claim, 7 Drawing Sheets

FIG. 1

FIG. 2

FIG. 3

FIG. 4

FIG. 5

FIG. 6

FIG. 7
